UNITED STATES PATENT OFFICE.

JOHN T. JANETTE, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,016,071.

Specification of Letters Patent.

Patented Jan. 30, 1912.

Application filed May 18, 1908. Serial No. 433,420.

To all whom it may concern:

Be it known that I, JOHN T. JANETTE, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

My invention relates to improvements in electric switches, and more particularly to those adapted to automatically open an electric circuit upon the occurrence of abnormal 15 conditions.

One object of my invention is to provide means which will cause the switch to close upon movement of the controller handle or other operating means and which will permit the switch to automatically open upon the occurrence of abnormal conditions, irrespective of the position of the operating 20 means.

A further object of my invention is to provide means which will insure the existence of normal conditions prior to the closure of the switch.

Other objects of my invention will be hereinafter set forth.

According to the preferred form of my invention, I connect the switch to a member which is normally free to move independently of the switch and I provide an electromagnet for causing said member, when 35 actuated, to operate the switch.

In order to more fully disclose my invention I have shown, in the accompanying drawings, a motor controller provided with a switch embodying one form thereof.

Of course, my invention may be embodied in various other forms and used in other 40 connections.

The views in the accompanying drawings are as follows:

Figure 1 is a front elevation of the controller with the front of the casing broken away to disclose the operating parts. Fig. 2 is a vertical sectional view taken through the lower part of Fig. 1, looking from the left-hand side. Fig. 3 is a horizontal sectional view taken on line 3-3, Fig. 1. Figs. 4 and 5 are enlarged horizontal views taken on line 4-4, Fig. 1, and showing the parts in dif-

ferent relative positions. Fig. 6 is a view similar to Figs. 4 and 5, but showing the parts in other positions, and for the purpose of better illustration, shows some of the parts in dotted lines. Figs. 7 and 8 are enlarged detailed views of parts of the device.

The various parts of the controller are enclosed within a casing 1. Vertically mounted within the casing, in suitable bearings 2 and 3, is a shaft 4 which carries a drum 5. The drum 5 carries a series of contact segments 6 which are arranged to successively engage a series of contacts 7, mounted on an insulating base 8 secured to the back of the casing 1. In practice, the contacts 7 are connected to a resistance connected in circuit with the motor armature. Mounted directly below the drum 5 is a horizontally disposed insulating base 9 which is supported in back by an angle bar 10 carried by the base 8, and in front by rods 11. The base 9 carries two contact segments 12 and 13 and also two series of contacts 14 and 15. The drum 5 carries two brushes 16 and 17. The brush 16 is adapted to move over the contact segment 13 and the series of contacts 14, while the brush 17 is adapted to move over contact segment 12 and the series of contacts 15. In practice, the contacts 14 and 15 are connected to a field resistance, while the contact segments 12 and 13 are connected in circuit with the field winding of the motor. A suitable operating handle 18 is keyed to the shaft 4. The term "handle" is hereinafter used to denote any operating means. As the handle 18 is moved from "off" position the drum 5 is rotated to first gradually remove the resistance from the armature circuit and then gradually insert the field resistance in circuit. The contact segments 12 and 13 are of sufficient length to insure all of the armature resistance being removed from circuit before the brushes 16 and 17 pass onto the contacts 14 and 15 to insert field resistance.

I shall now describe the switch mechanism which embodies my invention.

All of the parts which I shall now describe are carried by an insulating panel 19 which is secured to the back of the casing 1 in any suitable manner. At its upper right-hand corner the insulating panel 19 carries a bracket 20 provided with outwardly extending arms 21 and 22, which carry a pin 23

upon which is fulcrumed a main switch 24. Switch 24 is provided with tail pieces 25 adapted to engage the bracket 20 to limit the outward movement of said switch. A coil spring 26, interposed between the switch 24 and the base 19, tends to force said switch into its outermost position. At its forward end the switch 24 carries two spring arms 27 and 28 which are secured thereto by bolts 29. The spring arm 27 carries a contact 30 adapted to engage a carbon contact 31 carried in a frame 32 which is bolted, or otherwise secured to the supporting panel 19. The spring arm 28 carries a contact 33 adapted to engage a contact 34, which, as shown, is formed integral with the frame 32. Of course, the switch may assume various forms, the form shown serving merely for the purpose of illustration. The switch 24 is provided with a downwardly extending portion 35, which carries a forwardly extending ear 35^a adapted to support an arm 37. The arm 37 is fulcrumed on the switch 24 by a pin 36. Arm 37 is provided with a forwardly and outwardly extending portion 38 which carries a roller 39, and with a rearwardly extending portion 40 which carries a downwardly projecting pin 41. The roller 39 is adapted to be engaged by an insulating disk 42 carried by the shaft 4. The disk 42 is provided with a notched portion 43 in which the roller 39 rests when the operating handle of the shaft 4 is in "off" position. A coil spring 44, interposed between the portion 35 of the switch 24 and the forward portion of the arm 37, tends to maintain the roller 39 in engagement with the periphery of the disk 42. Mounted directly below the rear end of the arm 37 is an electromagnet 45 which is supported by its pole pieces 46 and 47, said pole pieces being secured to the panel 19 by screws 48. The pole piece 46 is cut away to receive one end of an armature member 49 which is fulcrumed on a pin 50 carried by said pole piece. The pole piece 47 is cut away to receive the free end of the armature member 49. The armature member 49 is provided with a longitudinally extending slot 51 in which the pin 41, carried by the arm 37, is adapted to work. For connecting the switch 24 in circuit I provide the same with a binding post 52 and the contacts 31 and 32 with a binding post 53. In practice, the magnet 45 is so connected in circuit that it will attract its armature member 49 so long as the voltage on the main line is normal and will release its armature member upon an abnormal decrease or failure of voltage on said circuit. Of course the magnet may be connected in circuit in various ways to accomplish its purpose.

I shall now describe the operation of my improved circuit controlling device.

65 Assuming that the operating handle of

the controller is in its "off" position, the roller 39 will rest in the notched portion of the disk 42, as shown in Fig. 6. If now the disk 42 be rotated, before the magnet 45 is energized, the inclined edge of the notch 43 therein will force the roller 39 inwardly, but this movement of the roller will only cause the arm 37 to rock on its fulcrum 36, throwing the armature 49 outwardly, as shown in Fig. 4. This movement of the arm 37 imparts practically no movement to the switch 24, and it will, therefore, be apparent that, until the magnet 45 attracts its armature, it will be impossible to close the switch 24. This arrangement protects the motor against damage in case the controller is carelessly operated. Assuming now that the magnet 45 is energized and attracts its armature 49, as shown in Fig. 6, the rear end of the arm 37 will be locked against lateral movement by the pin 41 carried thereby, which fits in the slot 51 in said armature. Hence, as the roller 39 is moved inwardly by the disk 42, it will move the entire arm 37 inwardly, and inasmuch as said arm is pivoted to the switch 24, it will also move said switch inwardly. When the disk 42 is rotated so far that the roller 39 engages its outer periphery the main switch will be closed, as shown in Fig. 5. In practice, the spring arms 27 and 28 are so arranged that the contact 30 will engage the carbon contact 31 before the contact 33 engages the contact 34 to diminish the arc formed upon the closure of the switch 24. Under ordinary circumstances, the switch 24 will be held closed during the continued rotation of the shaft 4 and will only be opened when the shaft 4 has been moved to "off" position, whereupon the roller 39 will again enter the notch 43 in the disk 42 and then the main switch will be forced open by the spring 26. If, however, the voltage on the main line fails at any time after the closure of the switch 24, the magnet 45 will be de-energized and release the free end of the armature member, thereby releasing the rear end of the arm 37. The spring 26 will then force the main switch 24 open without opposition. As the main switch 24 moves outwardly the arm 37 turns on its pivot 36 and throws the armature member 49 outwardly into the position shown in Fig. 4. The motor circuit is thus opened and cannot again be closed until the controller is moved to "off" position, when the roller 39 will enter the notch 43 in the disk 42. As the roller 39 enters the notch in the disk 42 the forward end of the arm 37 moves outwardly under the pressure of the spring 44, while its rear end moves inwardly, and through the medium of the pin 41 moves the armature member 49 into position to be again attracted to the pole piece 47 when normal conditions are restored.

As previously stated, after the main switch has been opened it will be impossible to again close the same without first moving the controller to "off" position. The foregoing is obvious, for, in order to again close the switch without returning the controller to starting position, the magnet 45 would have to attract its armature member against the opposition of the spring 26, which it is unable to do, even though normal voltage is immediately restored to the line.

Having thus described my invention, what I claim as new and desire to secure by Letters Patent is:

15 1. In combination, a switch, a member connected to said switch and movable independently thereof, and an electromagnet adapted to cause said member, when moved, to actuate said switch, said member being effective to operate said switch only while said electromagnet is energized.

2. In combination, a switch tending to stand in open position, a member connected to said switch and movable independently thereof, an electromagnet adapted to cause said member, when moved, to close said switch; said member, when released by said magnet, being adapted to release said switch.

3. In combination, a switch, an operating member therefor adapted to turn upon either of two pivots, said member being arranged to normally turn upon one pivot, and an electromagnet adapted, when energized, to necessitate said member being turned upon the other pivot.

4. In combination, a switch, an operating member therefor having two pivots, said member being arranged to normally turn upon one pivot independently of said switch, and an electromagnet adapted, when energized, to necessitate said member being turned upon the other pivot to actuate said switch.

5. In combination, a switch tending to return to initial position, an operating member therefor having two pivots, said member being arranged to normally turn upon one pivot independently of said switch, an electromagnet adapted, when energized, to necessitate said member being turned upon the other pivot to actuate said switch, said switch being adapted to be released upon deenergization of said magnet.

6. In combination, a switch, an arm pivoted to said switch, an electromagnet adapted to attract the end of said arm to cause said arm, when actuated, to close said switch, and means for opening said switch when said arm is released by said magnet.

7. In combination, a switch tending to stand in open position, a lever connected to said switch, a low-voltage magnet, said lever being fulcrumed to the armature of said magnet, said magnet being adapted to attract its armature to cause said lever, when

80 moved, to close said switch, said switch being adapted to automatically open when said magnet releases its armature.

8. In combination, a pivoted switch, a member pivoted intermediate of its ends to said switch, a low-voltage magnet having a pivoted armature, a pin carried at one end of said member adapted to work in a slot in said armature, said armature, when attracted by said magnet, being adapted to cause said member and said switch to move together, and means for opening said switch, irrespective of the position of said member, when said armature is released by said magnet.

9. The combination with a controller having an operating member, of a main line switch, a member connected to said switch and movable independently thereof, said member being adapted to be actuated by said operating member, and an electromagnet adapted to cause said member, when actuated, to close said main switch.

10. The combination with a controller having an operating member, of a main line switch tending to stand in open position, an arm connected to said switch and movable independently thereof, said arm being adapted to be actuated by said operating member, and an electromagnet having an armature member connected to said arm, said magnet being adapted to attract said armature to cause said arm, when actuated, to close said switch, said switch being adapted to open, irrespective of the position of said operating member, when said armature is released by said magnet.

11. The combination with a controller having an operating member, of a main line switch, an arm pivoted intermediate of its ends to said switch and adapted to be actuated by said operating member, an electromagnet having an armature connected to one end of said arm, said armature, when attracted by said magnet, being adapted to cause said arm, when actuated, to close said switch, and means for opening said switch, irrespective of the position of said operating member, when said armature is released by said magnet.

12. The combination with a controller having an operating member, of a main line switch tending to stand in open position, a lever connected to said switch and adapted to be actuated by said operating member, a low-voltage magnet having an armature, said lever being fulcrumed on said armature, said armature, when attracted by said magnet, being adapted to cause said arm, when actuated, to close said switch, and when released by said magnet to permit said switch to open, irrespective of the position of said operating member.

13. The combination with a controller having an operating shaft, of a pivoted

main line switch, an arm pivoted intermediate of its ends to said switch, a cam carried by said shaft adapted to engage one end of said arm, a low-voltage magnet having a pivoted armature, a pin carried at the opposite end of said arm adapted to work in a slot in said pivoted armature, said armature, when attracted by said magnet, being adapted to cause said arm, when actuated by said cam, to close said switch, and means for opening said switch, irrespective of the position of said cam, when said armature is released by said magnet.

14. The combination with the operating element of a controller, of a main line switch, an operating member connected to said switch and movable independently thereof, said member being arranged to be actuated by said element, an electromagnet adapted to cause said member, when moved by said element, to close said switch, and means for automatically opening said switch upon deenergization of said magnet,

and maintaining said switch in open position until said element is returned to initial 25 position.

15. The combination with the operating element of a controller, of a main line switch arranged to be actuated by said element, said switch being arranged to turn upon 30 either of two pivots and arranged to normally turn upon one pivot, and an electromagnet adapted, when energized, to necessitate said switch being turned upon the other pivot, and means for opening said switch upon deenergization of said magnet, and maintaining said switch in open position until said member and said element are returned to initial position.

In witness whereof, I have hereunto subscribed my name in the presence of two witnesses.

JOHN T. JANETTE.
